FUSED CUTOUT OF THE EXPOSED LINK
TYPE

David C. Hubbard, Centralia, Mo., assignor to
A. B. Chance Company, Centralia, Mo., a corporation of Missouri

Application December 19, 1947, Serial No. 792,805

9 Claims. (Cl. 200—117)

1

The present invention relates to fused cut-outs of the exposed link type, and is particularly concerned with the provision of a fused cut-out which is adapted to utilize any of the standard exposed fuse links now on the market.

One of the objects of the invention is the provision of an improved fused cut-out of the exposed link type, which is so constructed that the same spring which tensions the fuse link also tends to absorb the shock movement of the pivoted arm, but the structure is also so arranged that the spring cannot be damaged or tensioned beyond its elastic limit, if the lineman should carry the cut-out by means of its pivoted arm.

Another object of the invention is the provision of an improved fused cut-out of the class described, which interposes a minimum amount of resistance in the connections between the tap wire and the fuse link which is carried by the pivoted arm.

Another object of the invention is the provision of an improved construction for a fused cut-out of the class described which is simple in construction, sturdy, capable of economical manufacture and which is adapted to be used for a long period of time under all kinds of adverse weather conditions without failure, and without necessity for repair or replacement of any of its parts.

Another object of the invention is the provision of an improved fused cut-out construction, which may be supported either upon a single insulator or upon two separate insulators, the latter being accomplished by the use of an adapter which makes the connection between the top of insulators of the type carrying bolts and the arms of the present cut-out.

Other objects of the invention will be apparent from the following description and the accompanying drawings, in which similar characters of reference indicate similar parts throughout the several views.

Referring to the two sheets of drawings accompanying this specification,

Fig. 1 is a side elevational view of a fused cut-out embodying the invention;

Fig. 2 is a top plan view with the fuse link removed;

Fig. 3 is a bottom plan view of the cut-out of Figure 1, with the fuse link removed and with the arm in horizontal position;

Fig. 4 is a view similar to Figure 1 of a modification; and

Fig. 5 is a fragmentary plan view showing the adapter and mode of connection of the present

2

contact arms to the top of an insulator when the device is to be supported upon two insulators instead of one.

Referring to Figures 1 to 3, the present cut-out indicated in its entirety by the numeral 10, may be supported upon a single insulator 11 of the type having a central reduced cylindrical portion 12 for receiving a cylindrical clamping band 13 secured about the insulator by a bolt and nut 14.

10 The insulator 11 may be provided at each of its ends with a reduced substantially cylindrical portion 15, 16, having a diametrically extending through bore 17, 18. At the side opposite to the contact arms 19, 20, the cylindrical portions 15, 16, of the insulator 11 may be provided with substantially cylindrical sockets or enlarged counterbores 21, 22, adapted to receive the head 23 of a screw bolt 24, and also suitable metal and fibre washers 25, 26.

20 The bolts 24 preferably have a clearance in the bores 17 and 18 through which they pass freely, so that there is no tendency for the bolt to spread the bore and strain the insulator except to place the parts 15, 16 under compression.

25 The cut-out includes a fixed arm 19 and a movable arm 20, and both arms may have an identical construction at the link engaging end portion 27. The arms may be made of cast metal, and at the end portion 27 they are each provided with a substantially rectangular shank 28 which may carry one of two integral rearwardly extending hooks 29, 30. Two such hooks 29, 30, are preferably employed when it is desired to receive a new fuse link 31 while still holding the old fuse link.

30 In the absence of this requirement the end portions 29 may be provided with a single hook such as the hook 30, the other hook 29 being cut off or eliminated along the dotted line 32.

35 The entire end assembly 27 is preferably provided with a flat or plane top surface 33 so that this surface may flatly engage a complementary plane surface 34 on the fuse link ferrule 35, thus increasing the contact area and reducing contact resistance. The end portion 27 may have its end surface at 36 rounded, and each of the arms 29 and 30 forms, with the shank 28, a V-shaped opening 37 into which the leader 38 of the fuse link 31 may be wedged to effect a good low-resistance contact engagement.

40 The hook formations 29 and 30 extend diagonally outward from the shank 28 and may be substantially rectangular in cross-section, but may increase in thickness toward flaring ends 39, 40, which are intended to increase the size of

the tapered opening leading into the recesses 37 to make it easier to attach the fuse link 31, and to guide the leader 38 into the wedging recess 37. Thus the flaring ends 39 and 40 of the hooks comprise heads of increasing size rounded at their outer portions.

The standard fuse links, with which such contact arms are to be used, are of the exposed link type having a suitable insulating tube 41 which houses a fusible portion that joins the two leaders 38 and 42. Each leader is preferably provided with a ring formation 43, the edges of which are seen in Figure 1, and inside the ring and engaging it there is a ferrule 35 which engages the switch arm. Each ferrule 35 may have a cylindrical hub 44 which has a through bore for passing the leader 38 or 42, and each ferrule may have a radially extending disk 45 carrying the flat inner surface 34 that engages the contact arm.

Extending inwardly from the link supporting end 27 of the upper arm 19, this arm may gradually increase in depth and width to provide the desired cantilever strength, being provided with a pair of horizontally extending reinforcing ribs 46 and upwardly and downwardly extending ribs 47. At its attached end the contact arm 19 has a lateral enlargement in the form of a horizontal flange 48, which is bordered by an upwardly extending box like series of flanges 49, 50 and 51. These flanges 49—51 form an extension of the vertical rib 47, and provide a recess above the horizontal flange 48 of sufficient size to receive the end of the bolt 24 and the nut 52 and to permit the application of a wrench to the nut.

The flange 51 has a flat bearing surface 53 for the nut 52, but it is also preferably formed with radially extending wings 54 and 55 which are partially cylindrical, and which have the inner cylindrical surface 56 that is complementary to the cylindrical end portion 15 of the insulator 11. Thus the cylindrical surface 56 fits against the cylindrical surface 15 of the insulator, increases the bearing area of the metal arm 19 against the insulator, and the two complementary cylindrical surfaces 56 and 15 prevent rotation of the arm on the insulator so that the arm can be secured by means of a single bolt 24 which clamps it to the insulator.

Suitable spring washers are provided under the nut 52 for taking up rattling or any looseness and preventing the arm from getting loose in service. The flange 50 preferably supports a laterally projecting cylindrical lug 57, which is spaced from a laterally projecting lip 58 sufficiently to receive a tap wire 59 between lug 57 and lip 58. The lug 57 has a threaded end portion 60 for receiving the nut 61 which clamps the tap wire by means of a suitable washer.

The tap wire is preferably formed with a curved eyelet formation around the stud or lug 57 so that it cannot get off the lug 57, even when the nut becomes slightly loosened. Thus the upper arm 19 is adapted to be connected into the line, and it is supported at right angles to the insulator 11 in position to receive the upper end of fuse link 31.

The lower contact arm 20 is preferably longer than the upper contact arm 19 because the lower arm extends diagonally upward toward the upper arm. Lower arm 20 has its end formation 27 similar to that previously described for the upper arm. It also has a tapered and ribbed shank 62 extending from the hook end 27 backwardly to a cylindrical bearing formation 63. The bearing formation 63 has flat side surfaces 64, 65, and a

through bore 66 serving as a bearing for the pivotal support of the arm 20.

The inner end of the arm 20 also has a rearwardly extending spring supporting flange 67, which may form an extension of the lower rib 47 and which is provided with an aperture 68 for receiving the hooked end 69 of spring 70. Flange 67 tapers in depth toward the aperture 68. The spring 70 comprises a relatively heavy helical tension spring, which is provided at its other end with another hook formation 71 adapted to be hooked about a tubular spacer 72 which is carried by a rivet 73.

The length of the spring 70 is such that even when the arm 20 is horizontal, at minimum spring length the spring is already under initial tension. The rivet 73 and trunnion 74, which supports the bearing 63 of the arm 20, are in the same horizontal plane so that when the arm 20 extends diagonally upward, as shown in Figure 1, it is tensioned to rotate in a clockwise direction away from the arm 19.

The fixture 75 for supporting the pivoted arm 20 may consist of a cast metal member having parallel sides 76, 77, a top wall 78, rear wall 79 and part of a front wall 80. This box like fixture 75 houses the spring 70 and the pivotal supporting structure for the arm 20, and protects it from accumulations of ice and generally from the weather.

The side walls 76, 77, have lateral partially cylindrical wings 81, 82, which extend diagonally outward and are adapted to engage the cylindrical surface 16 on the lower end of the insulator 11. A screw bolt 83 passes through an aperture in the rear end wall 79, and is provided with a nut 84 by means of which fixture 75 is clamped to this end of the insulator. The arrangements for housing the head 23 of this bolt in a recess are exactly the same as described for the upper end of the insulator 11.

Although the lateral wings 81, 82 of the end wall 79 may be flat they provide a three-line contact with the cylindrical portion 16, and permit the mounting of the fixture 75 with a single bolt which secures it against turning.

The rivet 73 extends from side 76 to side wall 77, and preferably carries a tubular spacer 72 for supporting one end of the spring 70. In order to support the arm 20 for pivotal movement and to reduce resistance between the connections between the arm 20 and the line, I prefer to employ a connector plate 85 which carries the stub shaft 74 at right angles to the plate 85 at its right end. Stub shaft 74 extends through apertures 86 in the side plates 76 and 77 and has a threaded end provided with a nut 87.

The connector plate 85 engages the side plate 77 and is provided with an aperture 88 for receiving the rivet 73, which also secures the connector plate to the side of the housing 75. Connector plate 85 also has an integral laterally projecting cylindrical lug 89 which is screw threaded to receive a nut 90 which engages washer 91 and clamps the tap wire 92 to the connector plate. Tap wire 92 is preferably formed into a loop about the bolt 89, and the connector plate is provided with an integral stop lug 93 which holds the tap wire under the washer 91.

The operation of the fused cut-out is as follows: The fuse link 31 may be hung on a disconnect stick by means of its upper ring 43, and the lower leader 42 may then be brought into engagement with the hook formation 27 on the lower arm. The stick is then elevated lifting the

upper ring 43 and tensioning the spring 70 while the arm 20 pivots counterclockwise.

The fuse link 31 is lifted high enough so that the upper leader 38 may be hooked in one of the wedging recesses 37 on the upper arm 19. Then the stick is lowered until the ferrule 35 engages the upper arm 19 and then the stick is removed from the ring 43.

The tension exerted by the spring pressed arm 20 draws both leaders 38 and 42 tightly into the wedging recess 37 of the hooks 27. When the fuse 31 blows the arms 20 pulls the leaders 38 and 42 apart, pulling them out of one or both ends of the insulating tube 41 to assure a quick break of the circuit. Then the arm 20 swings downward under the pull of spring 70, but after the arm 20 passes the horizontal position the spring 70 absorbs the shock and brings the arm 20 to a stop.

In addition to this the end of the flange 68 acts as a stop for engaging the inside of the housing 75 positively preventing further movement. A positive stop is important because the linemen sometimes carry such a cut-out by means of its spring arm, and the spring might otherwise be tensioned beyond its elastic limit.

Referring now to Figure 4, this is a modification in which the point of pivot of the lower arm has been moved in closer to the insulator. The construction of the insulator 11 and the attachment of the two arms to the insulator may be exactly as described with respect to Figure 1. In this case, however, the lower housing may consist of a cast metal member having an upper wall 95, two side walls 96, front wall 97 and rear wall 98.

In this case the aperture 99 in the rear wall is close enough to the top wall 95 so that the top wall 95 holds the nut 100 against turning when the bolt is driven home by means of a wrench applied to the head 101. The rear wall 98 is again curved to fit the cylindrical portion 15 of the insulator. In this case also the top wall 95 of the housing preferably slants upward from the rear wall 98, and the lower arm 102 has an obtuse bend 103 below the front wall 97.

The purpose of the obtuse bend 103 is to bring the hook end 27 of the arm 102 up into the position corresponding to the length of the fuse link 31, while still having the arm 102 located below the housing 94. The front wall 97 of the housing 94 has a pair of apertures 104 in which the end 69 of the spring 70 may be hooked. The other end 71 is hooked in an aperture 105 in the upwardly extending flange 106 on the arm 102.

In this case the flange 106 extends upwardly from the bearing portion of the arm 102, which is pivotally mounted on the bolt 107. The walls 96 of the housing 94 are preferably provided with a front to rear reinforcing rib 108 and with a downwardly extending curved portion 109, these curved portions having apertures for the bolt 107.

The reinforcing rib 108 also serves to confine the tap wire 110 beneath the square washer 111 and adjacent the bolt 107. The same nut 112 and a suitable spring washer 113 are used to secure the bolt 107 in the housing 94, and to secure the tap wire 110 to the housing. The rear corner 114 of the arm 102 serves as a stop by engaging the lower edge of the rear wall 98 or the nut 100.

The operation of this fused cut-out is exactly the same as the preceding one, but as the lower arm 102 is pivoted adjacent the insulator 11 instead of being pivoted at the end of the housing 94 this brings the fuse link 31 closer to the in-

sulator 11, and the upper arm 115 may be made that much shorter.

The upper arm has a vertically extending rib 116 for engaging the tap wire 117, and the nut 118 has a square washer 119 engaging the tap wire.

The present fused cut-outs may also be mounted, with each arm carried by a different insulator; in such case the insulators 120 (Figure 5) are preferably of a type having a metal cap 121 which is threaded to receive a pair of screw bolts 122, 123. An adapter 124 may be employed for connecting any one of the arms 19, 20, 115, 102 or their fixtures to the insulator 120. For example, the connection of the fixture 75 is illustrated having the lateral wings 81, 82 and rear wall 79.

The adapter comprises a cast metal member provided with a pair of flat attaching flanges 125, 126, and with a central transversely extending cylindrical portion 127. The cylindrical portion 127 is hollow, being provided with a recess 128 for receiving the head 129 of the screw bolt 130. The recesses are closed by end walls 131, and the base 132 of each recess is flat and provided with an aperture 133 for receiving the bolt 130.

The rear wall 79 and wings 81, 82 fit against this cylindrical portion 127 just as they fit against the cylindrical portion 16 of the wing insulator 11. A suitable nut 134 is held against turning between the flanges of the housing 75 so that the bolt 130 can be driven home by a wrench applied to its head 129, thus securing the housing 75 to the adapter 124.

The attaching flanges 125 and 126 of the adapter have apertures 135 which register with the screw bolts 122, 123. Attaching flanges 125, 126 may thus be attached to the metal cap 121 by means of the screw bolts 122, 123 and a suitable spring lock washer 136. Thus the arms may be secured to an adapter which is so constructed that it can be secured to a metal cap 121 of an insulator 120 so that each arm is carried by a separate insulator, the insulators being mounted upon a metal bracket.

It will thus be observed that I have invented an improved fused cut-out of the exposed type in which the spring not only urges the arm in such a direction as to place a tension on the fuse link, but the same spring absorbs the shock and brings the arm to rest. In addition the cut-out has a positive stop so that a lineman cannot overstrain the spring by means of its pivoted arm.

The present pivoted arms are mounted with a minimum electrical resistance, as the arm is pivoted directly on an integral lug carried by the connector plate to which the tap wire is secured. The present cut-outs may be mounted upon a single insulator or by means of an adapter each arm may be mounted upon a separate insulator of the type having a metal cap with a pair of bolts.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In a fused cut-out, the combination of an

insulator having a cylindrical portion with a housing member having top and side walls and having its rear wall provided with an aperture, said side walls having diagonally extending wings for engaging the cylindrical portion of the insulator, said cylindrical portion having a through bore and a counterbore for housing a bolt and its head, said bolt passing through the rear wall and having a nut to clamp the housing to the insulator, a contact arm pivotally mounted in said housing and having at its free end a backwardly extending hook formation for engaging a fuse link leader and spring means in said housing for urging said contact arm in such a direction as to place a tension on the fuse link unit, the spring being tensioned between a part carried by said housing and a part on said contact arm, and being arranged to absorb the shock and bring the contact arm to a stop after the fuse blows.

2. In a fused cut-out, the combination of an insulator having a cylindrical portion with a housing member having top and side walls and having its rear wall provided with an aperture, said side walls having diagonally extending wings for engaging the cylindrical portion of the insulator, said cylindrical portion having a through bore and a counterbore for housing a bolt and its head, said bolt passing through the rear wall and having a nut to clamp the housing to the insulator, a contact arm pivotally mounted in said housing and having at its free end a backwardly extending hook formation for engaging a fuse link leader and spring means in said housing for urging said contact arm in such a direction as to place a tension on the fuse link unit, said contact arm being pivotally mounted upon a cylindrical stud extending through apertures in the side walls of said housing, said cylindrical stud forming an integral part of a connector plate having integral means for securing a tap wire to the plate.

3. In a fused cut-out, the combination of an insulator having a cylindrical portion with a housing member having top and side walls and having its rear wall provided with an aperture, said side walls having diagonally extending wings for engaging the cylindrical portion of the insulator, said cylindrical portion having a through bore and a counterbore for housing a bolt and its head, said bolt passing through the rear wall and having a nut to clamp the housing to the insulator, a contact arm pivotally mounted in said housing and having at its free end a backwardly extending hook formation for engaging a fuse link leader and spring means in said housing for urging said contact arm in such a direction as to place a tension on the fuse link unit, said contact arm being pivotally mounted upon a cylindrical stud extending through apertures in the side walls of said housing, said cylindrical stud forming an integral part of a connector plate having integral means for securing a tap wire to the plate, said latter means comprising an integral threaded stud provided with a nut and washer for engaging the tap wire and an integral finger for holding the tap wire against said stud.

4. In a fused cut-out of the exposed type, the combination of an insulator with a housing member carried by said insulator and projecting laterally from said insulator, said housing having parallel side walls and a top wall, a contact arm pivotally mounted on said housing between said parallel side walls, said contact arm having an

integral bearing formed on its rear end, and having a pair of integral backwardly and outwardly extending hooks formed on its free end, to provide a pair of V-shaped openings for receiving the cable of a fuse unit, and a connector plate carried by said housing, and having an integral pintle carried by said plate for pivotally mounting said contact arm with a minimum amount of resistance between the line connector and the contact arm.

5. In a fused cut-out of the exposed type, the combination of an insulator with a housing member carried by said insulator and projecting laterally from said insulator, said housing having parallel side walls and a top wall, a contact arm pivotally mounted on said housing between said parallel side walls, said contact arm having an integral bearing formed on its rear end, and having a pair of integral backwardly and outwardly extending hooks formed on its free end, to provide a pair of V-shaped openings for receiving the cable of a fuse unit, and a connector plate carried by said housing, and having an integral pintle carried by said plate for pivotally mounting said contact arm with a minimum amount of resistance between the line connector and the contact arm, the said connector plate carrying an integral stud and a lug adjacent said stud for confining a conductor, and a nut on said stud for clamping said conductor.

6. In a fused cut-out of the exposed type, the combination of an insulator with a housing member carried by said insulator and projecting laterally from said insulator, said housing having parallel side walls and a top wall, a contact arm pivotally mounted on said housing between said parallel side walls, said contact arm having an integral bearing formed on its rear end, and having a pair of integral backwardly and outwardly extending hooks formed on its free end, to provide a pair of V-shaped openings for receiving the cable of a fuse unit, and a spring having one end secured to said housing and the other end secured to said contact arm under tension for biasing the contact arm in a direction to tension a fuse unit, the spring acting also to absorb the shock when the contact arm is released by the fuse unit.

7. In a fused cut-out, a contact arm for engagement with the cable of an exposed unit, said arm comprising a cast metal member formed at one end with an integral bearing, said arm having an integral extension beyond said bearing for engagement with a spring, and said arm tapering in the opposite direction to its contact end, the contact end having an integral rearwardly extending hook, forming a V-opening for receiving the cable of a fuse unit, a forwardly open housing with parallel side walls and a pintle passing through said side walls and through said bearing for pivotally mounting said contact arm, and a spring extending from said extension to a transverse member carried by said parallel walls.

8. In a fused cut-out, a contact arm for engagement with the cable of an exposed unit, said arm comprising a cast metal member formed at one end with an integral bearing, said arm having an integral extension beyond said bearing for engagement with a spring, and said arm tapering in the opposite direction to its contact end, the contact end having an integral rearwardly extending hook, forming a V-opening for receiving the cable of a fuse unit, a forwardly open housing with parallel side walls and a pintle passing

through said side walls and through said bearing for pivotally mounting said contact arm, and a spring extending from said extension to a transverse member carried by said parallel walls, said transverse member comprising a rivet carrying a tubular spacer between said walls and said spring being hooked about said spacer.

9. In a fused cut-out, a contact arm for engagement with the cable of an exposed unit, said arm comprising a cast metal member formed at one end with an integral bearing, said arm having an integral extension beyond said bearing for engagement with a spring, and said arm tapering in the opposite direction to its contact end, the contact end having an integral rearwardly extending hook, forming a V-opening for receiving the cable of a fuse unit, a forwardly open housing with parallel side walls and a pintle passing through said side walls and through said bearing for pivotally mounting said contact arm, and a

spring extending from said extension to a transverse member carried by said parallel walls, said transverse member comprising a rivet carrying a tubular spacer between said walls and said spring being hooked about said spacer, and a connector carried by said rivet and being integrally connected with said pintle for securement of a conductor to the contact arm with a minimum amount of resistance.
